UNITED STATES PATENT OFFICE.

GEORGE K. GUINZBURG, OF NEW YORK, N. Y., ASSIGNEE TO I. B. KLEINERT RUBBER COMPANY, OF NEW YORK, N. Y., A CORPORATION OF NEW YORK.

GARMENT PROTECTOR.

Application filed June 11, 1921. Serial No. 478,673.

To all whom it may concern:

Be it known that I, GEORGE K. GUINZBURG, a citizen of the United States, and resident of the city, county, and State of New York, have invented a certain new and useful Improvement in Garment Protectors, of which the following is a specification.

This invention relates to a garment protector or baby pants usually worn by infants or young children to protect the outer clothing and the object of this invention is to provide a device of this character which may be worn comfortably at all times and which will be very effective in preventing the escape of moisture resulting in consequent damage to the child's outer clothing.

A further object of this invention is to provide a garment of this character which will be provided with an impervious or waterproof area where protection is required and which will also be provided with a pervious area or portion where protection is not required, permitting ventilation of the device and enabling the same to be worn with comfort at all times.

A still further object of the invention is to provide a garment of this character provided with side openings permitting a larger circumference of the top of the garment, and an improved reinforcing means at said side openings preventing tearing of the garment at those points and providing a strong and lasting construction.

With these objects and other objects which may hereinafter appear in view, I have devised the particular arrangement of parts hereinafter set forth and more particularly pointed out in the claims appended hereto.

Reference is to be had to the accompanying drawing, forming part hereof, in which—

Figure 1 is a front elevation of a garment protector made in accordance with my invention with a portion of the same being folded back to disclose the construction.

Figure 2 is a side elevation of a portion of the garment disclosing one of the side openings in open position and also disclosing the detachable fastening means therefor.

Figure 3 is a sectional view on the line 3—3 of Figure 2 looking in the direction of the arrows.

Figure 4 is a sectional view on the line 4—4 of Figure 1 looking in the direction of the arrows.

Figure 5 is a sectional view on the line 5—5 of Figure 2 looking in the direction of the arrows.

Throughout the various views of the drawings, similar reference characters designate similar parts.

In the preferred embodiment of my invention as disclosed in the accompanying drawing, I have shown my improved garment protector made from a single sheet of textile material. It will be obvious however, that the garment may be of any suitable material, a portion of which may be impervious and another portion pervious as will be hereinafter set forth.

The sheet of material from which my improved garment protector may be made is doubled upon itself to provide a front face 1 and a rear face 2, such faces being seamed together at their side edges providing the side seams 3. At 4 are shown the leg openings, said openings being expandable, the expansibility thereof being provided by means of the shirring 5 surrounding said openings and also by means of an expandable strip 70 secured in each opening and surrounding the same and secured therein by means of a line of stitches 7.

The side seams 2 of the garment which attach the faces 1 and 2 of the garment together at their side edges extend upwardly from one end of the leg openings 4 and terminate at their upper ends a distance below the waist band 8 of the garment. The waist band 8 of the garment is expandable to permit the garment to be readily placed on the wearer and such expansibility is provided by shirring the front and rear faces 1 and 2 of the garment as at 9 and also providing a flat expandable strip 10 on the inner faces of the garment over the shirring, said strip being secured in place by stitches 11.

The front faces 1 and 2 of the garment are not connected together at their side edges from the upper end of the side seams 3 to the 100 waist band and thus the side openings 11^a are provided.

By this construction a front flap 12 is provided and similarly a rear flap 13 is provided, the front flap 12 being merely an upward continuation of the front face 1 and the rear flap 13 is likewise an upward continuation of the rear face 2.

From the lower ends of the side openings 11 to the waist band, the front and rear faces 110

1 and 2, or in other words those portions thereof which form the front flap 12 and the rear flap 13, are of a pervious or "open" material to permit ventilation of the garment. These portions, constituting the flaps 12 and 13, are not located in an area where protection is required and consequently need not be made of an impervious material.

The rest of the garment, from the dotted line 14 downward is of an impervious or waterproofed material, the same being produced by filling in the interstices of the fabric with a waterproofing material. Thus the garment is provided in those parts where protection is required, with a waterproofed or impervious area, whereas those portions of the garment where protection is not required are of an "open" or pervious nature permitting ventilation.

20 The edges of the openings 11^a are each reinforced by means of a single continuous binding strip 15 which extends transversely across the side seam 3 and is secured in place by means of the stitches 16. The manner in 25 which this binding strip is secured in position greatly reinforces these side openings and particularly the upper end of each side seam 3. The binding 15 is transversely folded on the line of the seam 3 and to secure the front flaps 12 and 13 together at the 30 waist band, I provide detachable fastening means consisting of a button 17 and button hole 18 therefor. It will be understood however, that in place of the button and button hole, snap fasteners or other detachable 35 forms of fastening means may be used.

It will be seen that when the reinforcing binding strip 15 is folded transversely upon itself on the line of the seam 3 as at 19, the 40 two portions of the strip are brought together as disclosed in Figure 1.

It will also be seen from the foregoing that I have provided a garment which is shaped to fit the wearer snugly and is provided with suitable ventilating means in those portions where waterproof protection is not required and that those portions of the garment where protection is required are

of an impervious or waterproof material rendering the escape of moisture unlikely. 50

From the foregoing it is obvious that my invention is not to be restricted to the exact embodiment shown but is broad enough to cover all structures coming within the scope of the annexed claims. 55

What I claim is:

1. An article of the class described comprising a garment having a waist opening and side openings, said garment having a pervious area extending from the waist opening to the lower end of the side openings and an impervious portion extending from said side openings to the lower end of the garment and on all sides of the wearer. 60

2. An article of the class described comprising a garment having expandible waist and leg openings, said garment having side openings terminating a short distance below the waist line and fastening means for said side openings at the waist line of the garment, said garment being impervious below said side openings and pervious above said side openings. 70

3. An article of the class described comprising a garment having front and rear faces, said faces being seamed together at their side edges, the seams terminating at a distance below the waist band, said faces having an impervious portion terminating co-incidentally with the seams, and a pervious portion extending from the ends of the seams to the waist band. 75

4. An article of the class described comprising a garment having a front flap and a rear flap, fastening means on the waist band of said garment for uniting said flaps, said flaps each being shirred at their upper edge, a strip of expandible material secured to one face of each of said flaps over the shirring thereon, said flaps being made of a pervious material throughout their length with the body of the garment below said flaps made of an impervious material. 80

Signed at the city, county and State of New York this 9th day of June, 1921.

GEORGE K. GUINZBURG.
